[57] CLAIM

The ornamental design for a film holder, as shown and described.

DESCRIPTION

FIG. 1 is a perspective view of a film holder showing my new design;

FIG. 2 is an enlarged, top plan view of the film holder shown in FIG. 1, the bottom plan view being identical thereto;

FIG. 3 is an enlarged, left end elevational view thereof;

FIG. 4 is an enlarged, right end elevational view thereof; and

FIG. 5 is a rear elevational view thereof.
